UNITED STATES PATENT OFFICE.

WARNER R. BUXTON, OF LONGMEADOW, MASSACHUSETTS, ASSIGNOR TO BUXTON,
INCORPORATED, A CORPORATION OF MASSACHUSETTS.

KEY CASE.

Application filed December 7, 1921. Serial No. 520,591.

To all whom it may concern:

Be it known that I, WARNER R. BUXTON, a citizen of the United States, residing at Longmeadow, in the county of Hampden 5 and State of Massachusetts, have invented new and useful Improvements in Key Cases, of which the following is a specification.

This invention relates to cases for keys and the like and more particularly to cases 10 of the general type disclosed in U. S. Letters Patent No. 1,261,692, granted to me on April 2, 1918.

Cases of this particular type are made up from a strip of flexible material, such as 15 leather or the like, the end portions of which are folded in overlapping relation over the central portion to form an enclosure. The end portions, or flaps, are secured together by suitable means, such as 20 a glove fastener, which is usually applied centrally between the upper and lower ends of the case. Such ends are open but the key holders, being pivoted to the central portion of the case, are prevented from passing 25 out of the case by the two overlapping flaps which bear down upon them. The key holders are usually mounted upon a nonflexible member which extends across the central portion of the case near its upper 30 end and holds it in the desired flat form and the ends of this member lie approximately coincident with the lines of fold of said flaps and prevent the flaps from folding upon other lines which are closer together. 35 At the lower end of the case there is nothing to hold the central portion of the case in flat form nor to prevent the flaps from folding along other lines which are closer together than the usual lines of fold. Consequently, if pressure is brought to bear on 40 the sides of the case (defined by the lines of fold) and near the lower end thereof, the back or central portion of the case will bend rearwardly bringing the lines of fold of the 45 flaps closer together at their lower ends and making them converge downwardly instead of remaining parallel. When this happens, the upper ends of the flaps are caused to separate and bulge out from the key holder 50 supporting member, making a large opening through which some of the keys and their holders may drop out. That is, the flaps being pivotally connected intermediate their ends by the glove fastener, the inward

movement of the flaps at their lower ends 55 causes a separation of the flaps at their upper ends.

This invention is concerned with the provision of means for overcoming this difficulty and has for its object to provide a 60 member to lie between the lines of fold of the case and keep them properly spaced and thus keep the case and flaps in substantially flat form. This member resists pressure brought to bear on the sides of the case 65 and tends to prevent the sides being brought toward one another to an extent sufficient to open up the top of the case and allow the holders and keys to fall out.

A preferred means of accomplishing this 70 result consists of a member substantially coextensive in shape with the back of the case, which member is suitably fastened to the back, as along its upper edge. With this arrangement the key holder supporting device 75 may be fastened to this member and the rivets, by which the fastening is accomplished and which usually show from the outside of the case, are concealed.

The member described, if fastened merely 80 along its upper edge, may be swung outwardly when desired and the back of the member may be utilized incidentally to form part of a pocket for the reception of any desired articles, particularly license and 85 registration papers, which if kept with the keys are sure to be available when needed.

Other objects and advantages will appear in the following description and in the illustrative embodiment of the invention in 90 the accompanying drawings, in which:

Fig. 1 is an elevational view of a key case embodying my invention, the flaps thereof being shown in open position;

Fig. 2 is a similar view with the flaps 95 shown in closed position;

Fig. 3 is a cross-sectional view of the case;

Fig. 4 is a fragmentary rear view with the case largely broken away to reveal the 100 spacing member; and

Fig. 5 is a perspective view of a key case illustrating the condition which the spacing member is designed to overcome.

Referring to these drawings: The case 105 proper consists of a strip 10 of a flexible material, such as leather or the like, and the end portions 11 and 12 of this strip are adapted

to be folded along the lines 13 and 14 over the central portion 15 and to be secured in overlapping relation by any suitable means, such as a glove fastener, of which the male 5 and female sections are shown at 16 and 17 respectively. The fastening devices 16 and 17 are usually located centrally between the upper and lower edges of the flaps, as shown. Extending across the central portion 15, constituting the back of the key case, and disposed near its upper edge is a member 18, which is not readily flexible and is usually of thin metal, and from this member a series 10 of key holders 19, in the shape of snap hooks, are pivotally suspended. This member is supported by the back 15, in a manner which will later be described in detail, and its ends lie substantially coincident with the lines of fold 13 and 14. The member 18 prevents 15 bending of the back 15 near its upper edge, causes it to remain in flat form, and prevents the flaps 11 and 12 from being bent upon lines of fold which are any nearer together than those shown.

20 25 Ordinarily, no means is provided at the lower end of the case to prevent its sides from being forced toward one another as the result of pressure applied in the direction of the arrows 20 and at the general location shown in Fig. 5. Such pressure causes the back 15 to bulge rearwardly and the lines of fold are brought considerably closer together. The flaps 11 and 12, being fastened together centrally and in a pivotal 30 35 manner, an inward movement of the flaps at their lower ends causes the upper ends to move in a reverse manner and to spread apart and bulge outwardly from the back 15, leaving a relatively large opening at the top of the case through which keys and their 40 45 holders 19 may escape and also releasing these keys and holders from the restraining influence normally exerted by the folded flaps.

50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

ing the requisite stiffness to accomplish the result desired.

The key holder supporting plate 18 is fastened, as by rivets 25, to the member 22 and thus these rivets, which ordinarily pass through back 15, are concealed and the external appearance of the case materially improved. In addition to the improvement in appearance, the concealing of the rivets avoids a possible source of trouble which might otherwise occur due to the heads of the rivets catching upon the clothing, particularly the lining of the pocket in which the case is carried.

To further utilize the member 22, it may be made to form one wall of a pocket in which various articles may be carried, such as license and registration papers for example. While this object may be accomplished in various ways, I prefer to provide on the back of member 22 a somewhat shorter strip 26 which is secured to the member along the three coincident edges, as indicated by the stitchings 27, thus affording a pocket for the reception of papers, such as those indicated at p. A window 28 may be provided for the pocket, as in the member 26, if desired. The strip 26, in addition to its use in forming the pocket, reinforces the member 22 and increases its stiffness, aiding it in its work of keeping the case in flat form and resisting pressure applied to the sides of the case.

While the member 22 may be made up in other ways and mounted on the key case in other ways and still function in the described way and incidentally provide a pocket, the described arrangement is important and preferred in that the member is effective from end to end of the case and a maximum area of pocket space is afforded.

The invention has been disclosed herein, in an embodiment at present preferred, for illustrative purposes, but the scope of the invention is defined by the appended claims rather than by the foregoing description.

What I claim is—

1. A case for keys and the like, comprising, a strip of flexible material having a back portion and a flap on each side thereof, said flaps being foldable in overlapping relation over said back portion, a series of holders for keys and the like supported from said back portion near the upper edge thereof, and a reinforcing member substantially coextensive in width with the back portion and secured thereto, said member arranged to maintain the case in flat form and resist pressure applied so the sides of the case along the lines of fold of said flaps.

2. A case for keys and the like, comprising, a strip of flexible material having a back portion and a flap on each side thereof, said flaps being foldable in overlapping relation over said back portion, a member

- supported from the back and extending across the upper edge thereof with its ends substantially coincident with the lines of fold of said flap, a series of holders for keys and the like carried by said member, and a reinforcing member of substantially the same width as the back portion and secured thereto so that one end thereof extends across the back portion near its lower edge.
- 5 3. A case for keys and the like, comprising, a strip of flexible material having a back portion and a flap on each side thereof, said flaps being foldable in overlapping relation over said back portion, a member of substantially the same size and shape as the back portion and secured thereto along its upper edge, a series of holders for keys and the like, a support for said holders secured to said member near its upper edge, and a stiffening strip secured to said member and cooperating therewith to afford a pocket.
- 10 4. In a case for keys and the like, consisting of a strip of flexible material having its two end portions foldable over the central portion to form an enclosure, means for supporting keys or the like within said enclosure including a part secured to the central portion near its upper edge which part tends to prevent bending of the central portion along its upper edge, a member secured to the central portion and having a part substantially equal in width thereto
- 15 to minimize bending of the central portion near its lower edge, and a pocket provided in said member.
5. A case for keys and the like, comprising, a strip of flexible material having a back portion and a flap on each side thereof, said flaps being foldable in overlapping relation over said back portion, a member of substantially the same size and shape as the back portion and secured thereto along its upper edge, a series of holders for keys and the like, a support for said holders secured to said member near its upper edge, and a stiffening strip secured to said member and cooperating therewith to afford a pocket.
- 20 6. In a key case, in which the ends of a strip of flexible material are foldable over the central portion thereof, to afford an enclosure and a series of key holders are supported by said central portion near one end thereof by means which resist pressure on the sides of the case along the lines of fold of said flaps at such end, means mounted on said central portion and adapted to lie between the sides of the case near its lower end when the flaps are closed and keep them properly spaced.
- 25 7. In testimony whereof I have affixed my signature.
- 30
